UNITED STATES PATENT OFFICE.

STEPHEN E. PLUMMER, OF WHITMAN, ASSIGNOR OF ONE-THIRD TO E. GERRY BROWN, OF BOSTON, MASSACHUSETTS.

RECUTTING-MACHINE.

SPECIFICATION forming part of Letters Patent No. 451,434, dated April 28, 1891.

Application filed September 17, 1890. Serial No. 365,238. (No model.)

To all whom it may concern:

Be it known that I, STEPHEN E. PLUMMER, of Whitman, county of Plymouth, State of Massachusetts, have invented an Improvement in Recutting-Machines, of which the following description, in connection with the accompanying drawings, is a specification, like letters and figures on the drawings representing like parts.

10 In the manufacture of boots and shoes it is customary to lay patterns on the leather or other material used, and then to cut the material about the said patterns, and thereafter the said blanks so cut out are crimped to 15 give to them the proper shape, these crimped pieces being used not only for tops but for vamps, &c.

In crimping, owing to the differences in the various parts of the skin and to imperfect 20 placing on the crimping-former, the crimped edges of the superimposed parts of the crimped blank do not correspond and the crimped parts have to be recut, and in practice, so far as I am aware, this recutting has always been 25 done by hand.

The gist of my invention consists in the production of a machine by which to automatically perform the recutting, one or many crimped blanks being recut at one stroke.

30 In this embodiment of my invention I have chosen to illustrate the same in a machine or apparatus adapted to recut tops of Congress or button boots; but it will be obvious to those skilled in the art that by changing the 35 shape of the cutting-knives back pieces of shoes, vamps, boot-legs, backs and fronts, or any parts which have been crimped, may be readily recut to size and width, leaving their superimposed edges parallel.

40 In accordance with my invention I have provided a cross-head with a set of knives composed, as represented, of three parts, one knife being shaped to cut the rounded lower end of the blank, the other the top of the 45 blank, while the third knife cuts the corners between.

I have named three knives as preferable, for by such construction and attaching the said knives adjustably to a plate it is possible by merely changing the corner knife

for one of another size to enable many sizes of the same shape to be recut.

Figure 1 in front elevation represents one form of a recutting-machine embodying my invention; Figs. 2, 3, and 4, respectively, an under side view, a section, and a rear side elevation of the plate and its attached cutters. Figs. 5 and 6 show a cutter adapted for a larger size, the corner knife having been changed; Fig. 7, a plan view of the cutting-bed with its attached gages, the knives being shown in section.

The frame-work A is and may be of usual shape to sustain the working parts, the uprights A' A' thereof being slotted in usual 65 manner to receive the ends of the cross-head A², the ends of which are attached by links A³ to arms A⁴ of a rock-shaft A⁵, which in practice will have attached to it a suitable treadle in continuance of the arm A⁶, the 70 rock-shaft being turned to keep the cross-head normally elevated by a suitable spring, or it may be a counter-weight, all as usual.

The cross-head A² has attached to it by suitable bolts 2 the shank of a knife-carrying plate B. This plate (see Figs. 2 and 5) has bolted to its underside a block a, to which, by suitable screws 3, is secured the corner knife B', which cuts the corners 4 of the crimped blank, the said knife having preferably slots through which the said screws are entered, in order that the said knives may be readily changed for a wider or narrower one, according to the size of the blank to be recut, the said slots permitting the said corner knife 85 to be pulled off by simply slackening the said screws.

The corner 5 of any corner knife used always occupies one and the same position relatively to the plate B and the cutting-bed, but 90 the knives b and c co-operating with the said corner knife in order that the corner knife may be of greater or less size, as required, are attached to blocks b' c', in turn adjustably attached to the block a by screws b² c², 95 the block a having suitable lugs or projections to act as guides to insure the correct alignment of the straight parts 6 7 of the knives b c with the straight parts of the corner knife under all adjustments. The knife 100

b shapes the lower end of the blank *d* where the same, cut for a top, meets the usual fore part. The knife *c* is bent at its outer end, as at 8, to cut the upper end portion or end of the blank, to constitute, as shown, part of the top edge of the boot. It is obvious that these knives *b* and *c* may be shaped differently according to the particular shape of the blank to be recut, and it will be noticed that all blanks used in the construction of the main crimped parts of a boot or shoe have a corner 5 at some part of their length, from which corner the other knives start, and their particular contour will depend upon the shape desired for the extremities of the recut blank. For sake of brevity I shall denominate these knives *b* and *c* as "end knives."

The machine has a suitable table-plate *C*, which in practice will be made vertically adjustable by means of the screws *C' C'*, in order that it may be adjusted into the proper level according to the requirements of the knives. This table-plate supports a cutting-bed *D* of suitable material, preferably soft metal.

The bed *D* is slotted diagonally, as shown by dotted lines, Fig. 7, to receive lugs 10, (also shown by dotted lines,) said lugs being attached to the under side of a formation-gage 30 *E*, the acting edge of which conforms in shape to the acting edge of the crimping-form used in crimping the blank, the said formation-gage acting to position the crimped edge of the blank on the cutting-bed under the recutting-knives, so that as the said knives descend upon the blank they will cut it and leave both edges of the superimposed parts thereof parallel.

I may, if desired, recut a pile of crimped 40 blanks, one laid on the other, and I have recut successfully twelve blanks at one operation.

It will be understood in the manufacture of boots and shoes that the crimped blank for 45 a given number of boot or shoe will be of a certain length from the corner 4 to the top end 12, no matter what the width of the boot or shoe, it being well understood that manufacturers in making boots and shoes for market 50 make many different widths of the same length-size.

The knives will be first set for the size or number of the boot or shoe, and thereafter by the adjustment of the formation-gage the 55 different widths may be established.

Viewing Fig. 7, let *e* represent an adjustable size or length gage, and *f* a width-gage. Now to recut a No. 6 crimped blank (it being supposed that a No. 5 width is the largest to 60 be recut) the operator will put the corner 13 of the formation-gage at the largest width No. 5, and will then adjust the size or length gage to bring No. 6 to the corner 14, and thereafter as the sizes vary in length (in this 65 instance smaller sizes) the operator will adjust the gage *e* to place it into line suc-

sively with the smaller numbers on the length-gage. To recut larger sizes the formation-gage may be moved outwardly.

It will be obvious that my recutting-machine could be used to advantage even were all the knives in one piece, especially if any great number of blanks of the same width and length were to be cut at one time; but making the knives in three pieces, as described, 75 tends to economy and to rapidity of adjustment from one to another length.

I claim—

1. In a recutting-machine to recut crimped blanks, a blade-carrying plate having a removable corner blade and longitudinally-adjustable end blades, as described, of the proper contour, combined with a formation-gage to act against the crimped edge of the blank and with a width-gage to position said formation-gage, substantially as described.

2. In a recutting-machine to recut crimped blanks, a blade-carrying plate having a blade or blades, as described, of the proper contour, combined with a slotted bed and a formation-gage to act against the crimped edge of the blank and provided with lugs on its under side to enter said slots and with an adjustable size or length gage, substantially as described.

3. In a recutting-machine to recut crimped blanks, a blade-carrying plate having blades, as described, of the proper contour and adjustable, combined with a formation-gage to act against the crimped edge of the blank and with a width-gage and an independent adjustable size or length gage to co-operate with the formation-gage, substantially as described.

4. In a recutting-machine to recut crimped blanks, a cutting-bed and a knife-holder, combined with a corner knife and end knives adjustable with relation to the said corner knife in alignment with the sides thereof to adapt them to corner knives of any particular size, substantially as described.

5. The knife-holder having a block *a*, a corner knife connected thereto, and end knives, combined with adjustable blocks to which the said end knives are attached, substantially as described.

6. The knife-holder having a block *a*, a corner knife connected thereto, and end knives, combined with adjustable blocks to which the said end knives are attached, and with guides to insure the alignment of the straight parts 6 and 7 of the end knives with the corner knife in all adjustments of the said end knives, substantially as described.

In testimony whereof I have signed my name 125 to this specification in the presence of two subscribing witnesses.

STEPHEN E. PLUMMER.
